No. 37,289.

Patented January 3, 1905.

UNITED STATES PATENT OFFICE.

TIMOTHY CLEARY, OF SCHUYLERVILLE, NEW YORK, ASSIGNOR TO STANDARD WALL PAPER COMPANY, OF SANDYHILL, NEW YORK.

DESIGN FOR A WALL-COVERING.

SPECIFICATION forming part of Design No. 37,289, dated January 3, 1905.

Application filed December 5, 1904. Serial No. 235,640. Term of patent 14 years.

To all whom it may concern:

Be it known that I, TIMOTHY CLEARY, a citizen of the United States, and a resident of Schuylerville, in the county of Saratoga and State of New York, have invented a new, original, and ornamental Design for Wall-Coverings, reference being had to the accompanying drawing, in which the figure is a face view of a wall-covering showing my design.

I claim as new and desire to secure by Letters Patent—

The ornamental design for a wall-covering herein shown.

TIMOTHY CLEARY.
